UNITED STATES PATENT OFFICE.

JAMES M. LOCKEY, OF FAULKTON, SOUTH DAKOTA.

VAPORIZER.

SPECIFICATION forming part of Letters Patent No. 772,466, dated October 18, 1904.

Application filed August 10, 1903. Serial No. 168,872. (No model.)

To all whom it may concern:

Be it known that I, JAMES M. LOCKEY, a citizen of the United States, residing at Faulkton, in the county of Faulk and State of South Dakota, have invented certain new and useful Improvements in Vaporizers; and I do hereby declare the following to be a full, clear, and exact description of the invention, such as will enable others skilled in the art to which it applies to make and use the same.

My present invention relates to vaporizers adapted for use for medicinal purposes, and especially for the treatment of nasal, bronchial, and lung trouble, and has for its object to improve the construction of the same in the several particulars hereinafter noted.

To the above ends the invention consists of the novel devices and combinations of devices hereinafter described, and defined in the claims.

The invention is illustrated in the accompanying drawings, wherein like characters indicate like parts throughout the several views.

Figure 1 shows the apparatus in side elevation. Fig. 2 shows the apparatus partly in side elevation, but principally in vertical section. Fig. 3 is a perspective view of the detached nasal tube. Fig. 4 is a detail, partly in vertical section and partly in side elevation, showing the so-called "evaporating" chamber or cup and the vapor-outlet 22, said parts being separated; and Fig. 5 is a horizontal section on the line $\alpha^5 \alpha^5$ of Fig. 2.

As illustrated in the drawings, the numeral 1 indicates a rectangular housing which affords a base for the vaporizing apparatus proper, which vaporizing apparatus involves a cylindrical case 2, having at one side a door 3 and having at its top a removable dome-like cover 4. The case 2 and the door 3 are provided near their lower portions with air-inlet passages 5. The door 2 when opened permits the insertion of an alcohol-lamp 6 near the lower portion of the case 2, and to hold said lamp in working position the bottom of said case is formed with a shallow annular flange 7.

In the upper portion of the case 2 is a hollow spherical body 8, which affords the commingling-chamber, as will presently more

fully appear. An air-supplying tube 9 leads from a source of air-supplying pressure into the spherical chamber 8. As shown in the drawings, the said tube 9 leads from a fan 10, located within the shell 1. This fan may be driven in any suitable way by means not necessary for the purposes of this case to illustrate, since neither said fan nor the means for driving the same constitutes a feature of my present invention. The upper end of the tube 9 is passed through a perforation in the side of the case 2 and is telescoped into a short sleeve-like projection 11 of the commingling-chamber 8.

The numeral 12 indicates what is herein designated as the "nasal" tube, the same having at one end a stop-flange 13 and laterally-bent threaded end 14 and having at its opposite end a pair of prongs terminating in perforated nose-pieces 15. The threaded end 14 of said nasal tube is adapted to be inserted through a perforation in dome-like cover 4 and to be screwed into a threaded sleeve 16 of the commingling-chamber 8. When the said nasal tube is thus applied in working position, its flange 13 presses on top of the dome 4 and securely supports the commingling-chamber in working position.

Within the case 2, above the lamp 6 and below the commingling-chamber 8, is a water-containing cup 17, having a cover 18, into which is inserted either by screw-threaded engagement or by engagement under friction, so that the two parts will be detachably, but quite securely, held together, a smaller cup 19, which affords an evaporating-chamber 85 secured to or cast integral with the cover 18, so that it depends into the water 2, contained within the larger cup 17. The cover 18 is provided at its center with a funnel-like flange 20 and a screw-threaded perforation 21. The lower end of the vapor-tube 22 is adapted to be screwed into the perforation 21 and to be inserted through a closely-fitting perforation in the lower portion of the commingling chamber 8. A laterally-bent tube 23 is, as shown, rigidly secured to the cover 18 and communicates with the steam-chamber or water-jacket formed around the evaporating-cup 19.

within the water-cup 17. This laterally-bent tube 23 is passed outward through a perforation in the side of the case 2, and the sleeve-like end of a thin metallic bulb 24 is frictionally telescoped onto the same. This bulb 24 affords a condensing-chamber for the steam, which will enter the same from the cup 17 through the tube 23, and to prevent excessive pressure in said bulb it is provided with a vent or small perforation 25. The tube 23 assists in holding the cup 17 in working position, as shown in the drawings; but to further hold the same and the cover 18 and evaporating-cup 19 a horizontally-extended bracket 15 is secured to and within case 2, as best shown in Fig. 5. The inner end of the bracket 26 is bifurcated at 27, so that it embraces the funnel-like flange 20 of the cover 18. If desired, other devices may be used to hold the 20 said parts 17, 18, and 19 in working positions; but the above-described means will usually be found sufficient.

The medicine or curative substance which is to be commingled with the air to form a 25 vapor to be inhaled is placed within the evaporating-cup 19 and is preferably in liquid form, as indicated at z' in Fig. 2. The lamp 6 being then lighted, the water z will be boiled and more or less thereof converted into steam, 30 which steam will rise through the tube 23 into the condensing-bulb 24 and by contact with its relatively cold walls will be condensed and run back into the cup 17. The liquid medicine z' , while it cannot be burned by the hot 35 water and steam which surrounds the cup 19, will be heated to such an extent that a sufficient quantity thereof will be vaporized and will pass upward through the vapor-tube 22 into the commingling-chamber 8, where it 40 will be commingled with the air which is being driven through the air-supply tube 9 into the commingling-chamber 8 and out through the nasal tube 12. Hence the air which is delivered from the nasal tube will be medicated 45 or commingled with a vapor of the particular medicine which is being used. In case there should be a slight condensation of the vaporized medicine within the commingling-chamber 8 sufficient to leak through the joint between the vapor-tube 22 and the shell of the 50 commingling-chamber 8 such condensation would run down said tube and be caught by the funnel 20, from whence it will be permitted to run back into the cup 19 when the said

tube is unscrewed and removed from its seat 55 in the cover 18.

The apparatus described is capable of modifications within the scope of my invention as set forth and claimed.

What I claim, and desire to secure by Letters Patent of the United States of America, is as follows:

1. In a vaporizer, the combination with a case and a lamp in the lower portion thereof, of a commingling-chamber in the upper portion of said case, a water-jacketed medicine-cup within said case, above said lamp and below said commingling-chamber, and having communication with said commingling-chamber through a small tubular passage, said water-jacketed cup and said commingling-chamber being subject to the heat of said lamp, a fan having a discharge-tube leading into said commingling-chamber, and a discharge pipe or tube leading from the said commingling-chamber, substantially as described.

2. In a vaporizer, the combination with a water-jacket, medicine-cup and a commingling-chamber communicating therewith, of means for producing a flow of air through 80 said commingling-chamber, and a condensing-tube leading from the water-jacket of said medicine-cup, substantially as described.

3. In a vaporizer, the combination with a case 24, of a commingling-chamber 8 in the upper portion of said case, the air-supply tube 9 passed through the side of said case and delivering into said commingling-chamber, the air-outlet tube 12 leading from the upper portion of said commingling-chamber outward 90 through the upper portion of said case, the lamp 6 in the lower portion of said case, the water-jacketed medicine-cup made up of the cup-section 17 and 19, and cover 18, said cover 18 having the flange 20, and perforation 21, 95 the vapor-tube 22 fitting said perforation 21 and extending upward into said commingling-chamber 8, and the condensing-tube 23 extending from the water-jacket of said medicine-cup, out through said case and having at 100 its upper end a condensing-bulb 24, substantially as described.

In testimony whereof I have affixed my signature in presence of two witnesses.

JAMES M. LOCKEY.
